UNITED STATES PATENT OFFICE.

EMORY S. ENSIGN, OF EAST ORANGE, NEW JERSEY, ASSIGNOR TO ROSE ENSIGN, OF EAST ORANGE, NEW JERSEY.

WINDOW-LOCK.

1,311,597.

Specification of Letters Patent. Patented July 29, 1919.

Application filed January 14, 1918. Serial No. 211,893.

To all whom it may concern:

Be it known that I, EMORY S. ENSIGN, a citizen of the United States, residing at East Orange, in the county of Essex and 5 State of New Jersey, have invented a new and useful Window-Lock, of which the following is a specification.

This invention relates to window locks and is in the nature of an improvement on 10 my U. S. application No. 152,420, filed March 3, 1917, where I show an elastic connection between sash and frame.

The object of this invention is to show improved means for connecting the ends of the 15 elastic member, particularly such means as will permit entire removal of said member without dismounting the fixtures that hold it in position for use. Other features of novelty will appear in the following description.

20 In the drawings which accompany and form part of this specification,—

Figure 1 is a partial view of a double window sash with its frame, showing two of my 25 locks, one for each sash.

Fig. 2 is an enlarged view of the lower lock shown in Fig. 1.

Fig. 3 is a view of Fig. 2, taken at right angles thereto.

30 Fig. 4 is an under plan view, sectioned on line 4—4 of Fig. 2.

The lower and upper sashes are marked A and B respectively, and the casing in general is designated by the letter C.

35 Referring to Figs. 2, 3 and 4, I attach firmly to casing C, as by screws 2, a socket-piece 1 formed of bent sheet metal and partially embedded in the casing, as seen in Figs. 2 and 4. Communication to socket 3 of socket-piece 1 is obtained by a slot 4 adapted to receive the bent tongue 5 of 40 spring 6 in such a manner that spring 6, when positioned for use, must be turned through an arc of, say, 90 degrees from entering position, so that tongue 5 will lie across slot 4 and prevent the detachment of 45 spring 6. Thus, when positioned for use, spring 6 has, preferably, a limited, free, vertical and bodily movement with relation to 50 socket-piece 1.

The opposite end of spring 6 is looped in a manner somewhat similar to that shown in my previous application referred to, but

I here end the loop 7 at 8, somewhat above 55 the coiled portion of spring 6. For detach-

able engagement of end 8, I provide a plate 9 firmly attached to sash A by screws 10 and having a bent ear 11, somewhat rounded and perforated at 12 to slidably receive one leg 60 of loop 7.

By inspection of the drawings, it will be seen that slot 4 bears such a relation to the positions of end 8 and ear 11 that when spring 6 is lifted as far as slot 4 will permit, it must be slightly extended against its elasticity to permit end 8 to be detached from 65 ear 11. My reason for preferring this form of construction is two fold,—first, that careless handling of the spring when manipulating the window may not accidentally detach 70 end 8 from ear 11 and, second, that anyone tampering with the lock from the outside would have to extend the spring before it could be released. In practice, this extension would amount to no more than a stiffening of the lost motion inherent in mechanical movements of this character.

Either method of detachment, viz.—that of elongating slot 4 sufficiently to freely permit end 8 to leave ear 11, or that of entirely 80 relying on the extension of the coils of spring 6 to permit this disengagement, might be properly effective alone and I do not limit myself to the combined use of both methods. If it should be desirable that the latter 85 method only be employed, socket-piece 1 would be secured to the casing in a position rotated 90 degrees from that shown, and tongue 5 would be twisted so that, in use, it would still lie across slot 4; or, preferably, 90 tongue 5 would be so formed as to lie at an angle of 45 degrees across slot 4, when in use, and thus no change need be made in tongue 5 when rotating socket-piece 1 through the above 90 degrees. 95

After freeing end 8, as above, spring 6 may be allowed to hang from socket-piece 1 in inverted position (see dotted line in Fig. 4) and thus the liability of mis-laying spring 6 is avoided; or, if preferred, tongue 100 5 may be removed from socket-piece 1 and spring 6 be laid away until it is again desired to lock the window.

Socket-piece 1 and plate 9 are fixtures, but 105 very inconspicuous ones, and will not interfere with the ordinary manipulation of the window, when cleaning or repairing of same is required. My spring, therefore, may be either partially or wholly detached, when freeing the window for ordinary use. 110

For locking the upper sash B, precisely the same parts are used, but socket-piece 1 is secured to sash B and plate 9 is secured to the parting bead D, as seen in Fig. 1. In this way, sash A may be released and moved freely without interference from the lock on sash B, as said lock occupies only the space of parting bead D, between the sashes, and clearance can be cut in the weather strips 10 that ordinarily bridge this space.

If desired, plate 9 may be embedded flush in the wood and socket-piece 1 may also be entirely instead of partially embedded in strip E. In this way, ear 11 would form the 15 only fixed projection, and socket-piece 1 would be directly secured to casing C instead of strip E as shown, so that the latter could be moved or removed without interfering with the lock.

20 I do not limit myself to the precise construction shown.

What I claim is:

The combination of a window casing and

a window operatively mounted therein, with a flexible window lock comprising a close-coiled spiral spring; and means for exteriorly mounting said spring in a vertical position against said casing, said means comprising a tongue at one end of said spring that is horizontally disposed when said spring is so mounted, a socketed fixture provided with a slot communicating with the socket, said slot being adapted for the passage therethrough of said tongue when in register therewith, a second fixture, means 35 for removably securing the opposite end of said spring to said second fixture, and means for rigidly attaching said fixtures to said casing and window, one to each, with said slot vertically disposed. 40

In testimony whereof, I hereto affix my signature, in the presence of two witnesses.

EMORY S. ENSIGN.
